US00D916748S

(12) **United States Design Patent** (10) Patent No.: **US D916,748 S**
(45) Date of Patent: **** Apr. 20, 2021**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Imran Chaudhri**, San Francisco, CA (US); **Alan C. Dye**, San Francisco, CA (US); **Jonathan P. Ive**, San Francisco, CA (US); **Brian Andrew Schmitt**, San Francisco, CA (US); **Christopher Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/703,944**

(22) Filed: **Aug. 30, 2019**

Related U.S. Application Data

(63) Continuation of application No. 29/641,877, filed on Mar. 26, 2018, now Pat. No. Des. 858,553, which is a continuation of application No. 29/575,616, filed on Aug. 26, 2016, now Pat. No. Des. 813,892, which is a continuation of application No. 29/501,184, filed on Sep. 2, 2014, now Pat. No. Des. 765,693.

CLAIM

The ornamental design for a display screen or portion thereof with graphical user interface, as shown and described.

DESCRIPTION

FIG. 1 is a front view of a display screen or portion thereof with graphical user interface showing a first embodiment of the claimed design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof; and,

FIG. 6 is a front view of a sixth embodiment thereof.

The outermost broken lines in the figures show a display screen or portion thereof, and form no part of the claimed design. The other broken lines in the figures show portions of the graphical user interface that form no part of the claimed design.

1 Claim, 6 Drawing Sheets

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : D916,748 S
APPLICATION NO. : 29/703944
DATED : April 20, 2021
INVENTOR(S) : Chaudhri et al.

Page 1 of 1

It is certified that error appears in the above-identified patent and that said Letters Patent is hereby corrected as shown below:

On the Title Page

Page 3 In the "Description" item (57), please replace the following paragraph:
"The outermost broken lines in the figures show a display screen or portion thereof, and form no part of the claimed design. The other broken lines in the figures show portions of the graphical user interface that form no part of the claimed design."

With:

--The outermost broken lines in the figures show a display screen or portion thereof, and form no part of the claimed design. The other broken lines in the figures show portions of the graphical user interface that form no part of the claimed design.--

Signed and Sealed this
First Day of June, 2021

Drew Hirshfeld
